UNITED STATES PATENT OFFICE.

JERRY T. VINE, OF SEATTLE, WASHINGTON, ASSIGNOR OF ONE-HALF TO THOMAS CONROY, OF SEATTLE, WASHINGTON.

AUTOMATIC PUMP CONTROL.

1,392,372.

Specification of Letters Patent.

Patented Oct. 4, 1921.

Application filed May 25, 1920. Serial No. 384,058.

To all whom it may concern:

Be it known that I, JERRY T. VINE, a citizen of the United States, residing at Seattle, in the county of King, State of Washington, have invented certain new and useful Improvements in Automatic Pump Controls; and I do hereby declare the following to be a full, clear, and exact description of the invention, such as will enable others skilled in the art to which it appertains to make and use the same.

This invention relates to air pumps, and more especially to pressure control mechanism whereby the operation of the pump is regulated by the amount of air stored; and the broad object of the invention is to provide means for starting or stopping the action of the pump rather quickly when the pressure has increased or decreased to certain limits.

This object is carried out by means of an improved pawl and ratchet mechanism connected with a clutch between the driving shaft and the pump, such mechanism being actuated by a piston moved in one direction by air pressure and in the opposite direction by a spring.

Details are set forth below and shown in the drawings wherein:

Figure 1 is a general side elevation of this structure complete, partly in section.

Fig. 2 is an enlarged detail of certain parts with the rocker at the midlength of its travel.

The invention herein is described as employed in connection with an ordinary pump P driven from a power shaft D for storing air in a tank T, from which it is drawn for use from time to time through a service pipe S, although of course it could be used in other connections. As herein shown, the shaft D has a power pinion 1 meshing with the gear 2 mounted loosely on a crank shaft 3, to whose crank 4 is connected the pitman 5 which leads to the piston within the pump P not necessary to illustrate; and a clutch 6 splined on the shaft 3 is adapted to be moved into active engagement with the gear 2 by a rod 7 which is connected to a fork 8 loosely engaging the hub of said clutch. When the latter is advanced by pushing on the rod, the pump commences to work; and when the rod is drawn on to retract the element 6 and open the clutch, the pump ceases its work. Its upper end is connected by a

pipe 9 with the tank T, the pipe having a check valve 10. In one end of the tank is a cylinder 11 within which is movably mounted a piston 12 borne normally inward toward the tank by a strong spring 13, and a rod 14 is connected with the piston and passes through the spring and outward beyond the cylinder for the purpose of swinging a lever 15 to which the rod 7 is attached at the point 17. The lever is herein shown as pivoted at its lower end at the point 16, and carrying mechanism at its upper end for retarding or delaying its swinging movement in either direction, as will be explained.

Pivots supported near each end of a fixed beam 20 is a ratchet wheel 21 on which rests the free end of a tension spring 22 which is secured at its other end at 23 to the beam and is capable of adjustment by means of a nut 24 on a stud bolt 25; and the springs 22 are so disposed that the ratchet wheels may turn outward or away from each other, but may not rotate in the opposite direction.

Pivots mounted at 30 on the upper end of the lever 15 is a rocker consisting of a head 31 and a stem 32 depending rigidly from its midlength and connected at 34 with the rod 14, while each end of the head carries an upstanding pawl 35 hooked inward as shown at 36; and as seen in Fig. 2, the distance between the pawls 35 is less than the distance between the outside of the two wheels 21.

With this construction of parts, when the air pressure falls within the tank, the expansion of the spring 13 draws on rod 14, swings lever 15 to the left and closes the clutch, and power is communicated to the pump to drive the latter and build up the pressure. If use is constantly made of the energy thus stored, the pump continues to operate and replenish the air exhausted. But if the air is not taken from the tank, in time the pressure will move the piston 12 against the spring 13 and will push on the rod 14. This results in swinging the rocker on its pivot 30 until its head 31 stands substantially horizontal and both pawls disengaged from the ratchets, and continued movement of the rod 14 then swings the lever outward with the head, while the pawls travel beneath the beam 20 as shown in Fig. 2. Movement of the lever 15 draws on the rod 7 and opens the clutch or otherwise controls

the power which drives the pump, and the latter ceases to operate. Continued movement of the parts to the right from the position shown in Fig. 2 eventually causes the 5 tip of the right hand pawl to pass the end of the beam 20, when it engages the teeth on the under side of the ratchet, and travels around beneath the same and up on its outer side—the parts coming to rest as seen in 10 Fig. 1. Now with the pump out of action, as soon as the stored energy is reduced as by withdrawal of some of the air within the tank, the pressure against the piston 12 decreases until the spring acts to move it in- 15 ward; this draws on the rod 14, pulls on the stem 32 of the rocker, and tilts its head 31 whenever the downward tendency of the right hand pawl whose hook 36 engages the ratchet, is sufficient to overcome the tension 20 of the spring 22 which retards the rotation of this ratchet. But as soon as the rocker is restored to its horizontal position, the left pawl strikes beneath the beam 20 and the right pawl drops to a point where it will 25 move under said beam as the rod 14 is moved to the left by the expansion of the spring 13. This movement swings the lever 15 which controls the power, and the pump again commences to work. As the lever 30 swings to its extreme inner position, the rocker tilts in a direction opposite to that shown in Fig. 1 and its left hand pawl 35 rises beyond the left hand ratchet and its hook 36 engages therewith. Continued ac- 35 tion of the pump will build up energy in the tank T, and eventually the piston 12 will again be moved outward to repeat the operation above described.

Thus it will be seen that the primary func- 40 tion of this device is to retard the movement of the lever 15 until the pressure has risen so high or fallen so low that a push or pull on the rod 14 will overcome the resistance set up by the tension spring 22 bearing 45 against that ratchet wheel 21 which is en- gaged by the pawl; but when this takes place and the lever commences to move, it is moved quickly to its opposite extreme position and there latched in practically the same way 50 against its return movement. It will be ob- vious that the clutch mechanism herein shown and described is merely illustrative of one means for connecting the power with the pump, which means is controlled by 55 movement of the lever 15. Any appropriate connection could be employed, and in fact the movement of the lever could stop and start the motor which drives the pump. Also it will be clear that the energy stored by the 60 action of the pump need not necessarily be compressed air, the element T might in fact be a reservoir to contain water, and the pis- ton could be replaced by any element which was controlled by the pressure of the water

or other agent which represented the work 65 performed. Therefore the broadest latitude must be given to the language herein em- ployed.

What is claimed is:

1. The combination with a power driven 70 pump, a power control lever, a tank to which the pump delivers, a cylinder projecting from the tank, a piston in the cylinder moved in one direction by accumulated en- 75 ergy, and a spring moving the piston in the other direction; of a rocker pivoted to said lever and having latches at its opposite ends for holding the lever at either extreme posi- 80 tion, and connections between said piston and rocker whereby movement of the piston will first turn the rocker to unlatch it and then swing the lever to its opposite extreme.

2. The combination with a power driven 85 pump, a power control lever, a tank to which the pump delivers, a cylinder projecting 90 from the tank, a piston in the cylinder moved in one direction by accumulated en- ergy, and a spring moving the piston in the other direction; of a T-shaped rocker pivoted at its angle to said lever, pawls project- 95 ing from the extremities of its head, ratchets with one of which a pawl is adapted to en- gage in either extreme position of the lever, tension means for retarding the movements of said ratchets, and a rod connecting the stem of the rocker with said piston.

3. In a mechanism of the type described, the combination with a swinging lever, a T-shaped rocker pivoted at its angle to the lever, a rod pivoted to the stem of the rocker, and means for moving the rod longitudinally; of a beam fixed above the head of said rocker, pawls rising from its extremities and having hooked ends, ratchet wheels carried by the beam and spaced a greater distance 105 from each other than are said pawls, and tension means for retarding the rotation of said wheels.

4. In a mechanism of the type described, the combination with a swinging lever, a 110 T-shaped rocker pivoted at its angle to the lever, a rod pivoted to the stem of the rocker, and means for moving the rod longitudinally; of a beam fixed above the head of said rocker; pawls rising from its extremities and having their ends hooked inward, ratchet wheels mounted in said beam with their teeth facing upward at their outer sides, said sides being spaced a greater distance 115 from each other than are the pawls, and tension springs on the beam engaging said wheels.

In testimony whereof I affix my signature, in the presence of two witnesses.

JERRY T. VINE.
